(57) CLAIM

The ornamental design for a guitar, as shown and described.

DESCRIPTION

The patent or application file contains at least one drawing executed in color. Copies of this patent or patent application publication with color drawing(s) will be provided by the Office upon request and payment of the necessary fee.

1. Guitar

1.1 : Perspective

1.2 : Front

1.3 : Back

1.4 : Left

1.5 : Right

1.6 : Top

1.7 : Bottom

1.8 : Reference

This article is a guitar; the color, yellow, represents non-claimed portions of claimed design and forms no part of claimed design; the black area shown in each view is for the purpose of illustrating the background of each view and forms no part of claimed design; 1.8 is a reference view showing guitar with armrest folded.
